(57) **CLAIM**

The ornamental design for a biopsy device handle, as shown and described.

DESCRIPTION

FIG. 1 is a perspective view of a biopsy device handle, showing the new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken lines shown in FIGS. 1-7 illustrate portions of the biopsy device handle that form no part of the claimed design.
